UNITED STATES PATENT OFFICE.

JOHN T. RIDDELL, OF EVANSTON, ILLINOIS.

ATHLETIC SHOE.

Application filed October 5, 1923. Serial No. 666,834.

My invention relates to improvements in athletic shoes, especially adapted for use by foot-ball players, the object of the invention being to provide a simple and efficient tread member for such shoes which will serve to prevent slipping and will not injure other players.

Other objects will appear hereinafter.

The invention consists in the combinations and arrangements of parts hereinafter described.

The invention will be best understood by reference to the accompanying drawing forming a part of this specification and in which,

Fig. 1 is a bottom plan view of a shoe equipped with tread members embodying the invention;

Fig. 2 an enlarged section taken on line 20 2-2 of Fig. 1;

Fig. 3 a section of a modified form of construction.

The form of construction illustrated in Figs. 1 and 2 comprises a rubber tread member 5 having a headed bolt 6 embedded therein with the threaded shank of said bolt projecting from the base of said tread member. An internally threaded socket member 7 is fitted into a recess 8 in the lower portion of the shoe sole, said socket member being provided at its lower end with a stop flange 9 fitting against a washer 10 resting against the bottom of the shoe sole 11. The socket member 7 is held in place by means of a threaded stud 12 provided with a relatively large head 13, said stud extending through the upper portion of the shoe sole to engage said socket member. The head 13 of the stud 12 is covered by the usual insole 14 as shown. In use a number of such tread members are applied to the sole and heel of the shoe as shown. By this arrangement a simple and effective tread member is provided which will effectively prevent slipping and will not injure other players. When worn the tread members may be readily removed and may be applied to the shoe by unskilled persons when desired. The shoe sole is clamped between the stud 50 12 and the socket member 7 which serves to reinforce the sole and distribute the back pressure so as to prevent injury to the foot.

In the modified form of construction illustrated in Fig. 3, an internally threaded socket member 15 is provided with a head 16 formed integral therewith, said socket

member extending through the sole of the shoe as shown. The lower end of the socket member is also externally threaded and a nut 17 engaged therewith to rest upon the washer 10 and hold the socket member in place and clamp the shoe sole. Otherwise the construction is the same as that already described.

While I have illustrated and described the preferred forms of construction for carrying my invention into effect, these are capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent, is:

1. The combination with a shoe, of a clamping member mounted in the sole thereof and having a threaded socket, said clamping member being made in two separable parts secured together, each part having a head on its end and said heads cooperating to clamp the sole between them; and a tread member having a threaded stud 80 to fit said socket, substantially as described.

2. The combination with a shoe, of an internally threaded socket member fitting into a recess in the lower portion of the sole thereof, said socket member being provided with a stop flange fitting against the bottom of the sole; a headed stud projecting downwardly through said sole and threaded to engage the upper threads of said socket, said stud and socket member 90 extending through and clamping the sole between them; and a tread member of relatively softer material having a headed stud embedded therein and projecting therefrom to engage the lower threads in said socket, 100 substantially as described.

3. The combination with a shoe, of an internally threaded socket member fitting into a recess in the lower portion of the sole thereof, said socket member being provided with a stop flange fitting against the bottom of the sole; a headed stud projecting downwardly through said sole and threaded to engage the upper threads of said socket, said stud and socket member 105 extending through and clamping the sole between them; a tread member of relatively 110

- softer material having a headed stud embedded therein and projecting therefrom to engage the lower threads in said socket; and a washer interposed between the flange 5 on said socket member and the bottom of the sole, said tread member being recessed to fit over the flange on said socket member and rest against said washer, substantially as described.
- 10 4. The combination with a shoe, of a washer engaging the bottom of the sole thereof; cooperating means consisting of screw thread engaging clamping means; a head provided on the upper end of one of 15 said members for clamping down on said sole, and the other member adapted to engage said washer, for clamping said washer in engagement with said sole; one of said clamping members being provided with an 20 internally threaded socket; a tread member having a headed stud imbedded therein and projecting therefrom, to engage threads in said socket; said tread member being recessed for receiving one of said cooperating means therein and adapted to engage said washer.
5. The combination with a shoe of cooperating means, consisting of clamping members; each of said clamping members being provided with a head; said members 30 adapted to engage each other, and to be secured from disengagement, for clamping said sole between said heads; one of said members having an internally threaded socket; and a tread member of relatively 35 soft material having a headed stud imbedded therein and projecting therefrom, to engage threads in said socket.

In testimony whereof I have signed my name to this specification.

JOHN T. RIDDELL.
